DESIGN FOR A COMBINED WAFFLE IRON AND TRAY

Alvin Feder, Chicago, Ill.

Application July 13, 1948, Serial No. 147,527

Term of patent 7 years

(CL D81—10)

To all whom it may concern:

Be it known that I, Alvin Feder, a citizen of the United States, residing at Chicago, in the county of Cook and State of Illinois, have invented a new, original, and ornamental Design for a Combined Waffle Iron and Tray, of which the following is a specification, reference being had to the accompanying drawing, forming part thereof.

Figures 3 and 4 are opposite end elevational views of the same.

I claim:

The ornamental design for a combined waffle iron and tray, substantially as shown.

ALVIN FEDER.
